[57] CLAIM

The ornamental design for a removable shoe protector,
or similar article as shown and described.

DESCRIPTION

FIG. 1 is a perspective view of a removable shoe pro-
tector, or similar article, in a position of use, showing
my new design.

FIG. 2 is a side elevational view, the opposite side ele-
vational view being a mirror image thereof.

FIG. 3 is a front elevational view thereof.

FIG. 4 is a rear elevational view thereof.

FIG. 5 is a top plan view thereof.

FIG. 6 is a bottom plan view thereof.

FIG. 1

FIG. 2

FIG. 3

FIG. 4

FIG. 5.

FIG. 6
